UNITED STATES PATENT OFFICE.

VICTOR E. EDWARDS, OF WORCESTER, MASSACHUSETTS, ASSIGNOR TO MORGAN CONSTRUCTION COMPANY, OF WORCESTER, MASSACHUSETTS, A CORPORATION OF MASSACHUSETTS.

GUIDE FOR ROLLING-MILLS.

No. 895,442.

Specification of Letters Patent.

Patented Aug. 11, 1908.

Application filed October 13, 1905. Serial No. 282,667.

To all whom it may concern:

Be it known that I, VICTOR E. EDWARDS, a citizen of the United States, residing at Worcester, in the county of Worcester and 5 Commonwealth of Massachusetts, have invented a new and useful Improvement in Guides for Rolling-Mills, of which the following is a specification containing a full and clear description of my improved guide and 10 accompanied by drawings illustrating the construction of the guide and its application to the consecutive rolls of a rolling mill.

The object of my present invention is to provide a guide for conducting the metal from 15 one pair of rolls to a second pair of rolls in a continuous rolling mill, whereby the continuous reduction of the metal is accomplished by a series of pairs of rolls operating consecutively upon the metal.

20 The guide embodying my present invention comprises a trough or conveyer by which the metal is conducted from one pair of rolls to the next consecutive pair; a delivery guide for delivering the metal from the 25 first pair of rolls to the trough or conveyer and a receiving guide at the opposite end of the trough or conveyer by which the metal is received and brought into alinement with the pass of the second pair of rolls.

30 The object of my invention is to simplify the construction in devices of this class and especially to obviate the liability of breakage due to an interruption in the movement of the metal from one pair of rolls to the other, 35 and to this end my invention consists in certain novel features of construction and arrangement of parts as hereinafter described and set forth in the annexed claims.

In the drawings accompanying this specification and forming a part thereof, Figure 1 40 represents a plan view of a guide by which metal is conducted from one pair of rolls in a rolling mill to the next consecutive pair of rolls. Fig. 2 is a detached and plan view of the delivery guide box with the stripping plates removed. Fig. 3 is a transverse sectional view of the trough or conveyer. Fig. 4 is a detached and plan view of the receiving 45 guide box with the cover removed in order to disclose the laterally adjustable check-plates by which the metal is brought into alinement with the pass in the second pair of rolls, and Fig. 5 is a central vertical sectional view of a 50 rolling mill guide embodying my invention.

Similar reference letters and figures refer 55 to similar parts in the different views.

Referring to the accompanying drawings A, A denote the housings of a pair of rolls A¹, A² of the rolling mill.

B, B, denote housings of a second and consecutive pair of rolls B¹, B².

The pass C in the pair of rolls A¹, A², is connected with the pass D in the second pair of rolls B¹, B², by means of a guide embodying my present invention, having its opposite 65 ends supported by horizontal shelves E and F attached to the roll housings A and B respectively.

Supported upon the shelf E is a guide box 1 comprising a bottom 2 and parallel vertical sides 3, 3, which are open at the top. The guide box 1 is attached to the shelf E by a bolt 4. The under side of the bottom 2 is provided with a transverse shoulder 5 and the shelf E has a similar transverse shoulder 6. Between the shoulders 5 and 6 are inserted wedges 7, 7, by which the guide box 1 is adjusted on the shelf E relatively to the rolls A¹, A², the bolt 4 passing through the slot 8 in the bottom of the guide box to 75 permit such adjustment. The bottom 2 of the guide box is also provided on its upper surface with shoulders 9 against which the rear end of the lower stripping plate 10 bears. The upper surface of the bottom 2 beneath the stripping plate 10 is slightly inclined at 11 to enable the stripping plate 10 to be supported at its rear end upon the bottom 2 and at its forward end by the periphery of the roll A².

90 Frictionally held between the sides 3, 3, of the guide box is a block 12 having one end bearing against one of the sides 3, and its opposite end receiving the pressure of a set screw 13. The block 12 is provided with a 95 pair of projecting pins 14 beneath which is inserted the rear end of the upper stripping plate 15. The rear end of the stripping plate 15 bears against the block 12, and the forward end is brought into contact with the 100 periphery of the roll A¹ by the lateral adjustment of the block 12 in the guide box. The adjustment of the stripping plates 10 and 15 is accomplished by placing the lower stripping plate 10 in position with its rear 105 end bearing against the shoulders 9 and forcing the box 1 forward by the wedges 7, 7, until the opposite end of the stripping

plate is brought into proper position against the periphery of the roll A^1 , and the upper stripping plate 15 is brought into proper position by the adjustment of the block 12 5 between the sides 3 of the guide box, the desired space between the stripping plates 10 and 15 being determined by the temporary insertion of a piece of metal of the desired thickness of the metal rolled between 10 the rolls A^1 , A^2 . The upper stripping plate 15 is suspended between the rolls and the block 12 from a rod 16 held in the housing A by means of a spiral spring 17, by which an upward pull is exerted upon the stripping 15 plate 15 to hold its forward end in contact with the periphery of the roll A^1 . By the above described method of holding the stripping plates 10 and 15, the above plates are easily removable and any interruption in 20 the process of rolling which causes an accumulation of metal in the guide box will serve to knock out the upper stripping plate and block 12 as the latter is held by friction only, thereby causing an accumulation of metal to 25 free itself. The free ends of the stripping plates 10 and 15 are concaved on the side next the rolls to form thin edges which, resting against the periphery of the pass, serves to strip the metal from the roll.

30 The metal, after passing the rolls A^1 , A^2 , is forced between the stripping plates 10 and 15 and through the guide box 1 into a conveyer trough 18, and from the conveyer trough 18 it is received into a receiving guide box 19, 35 which rests upon the horizontal shelf F and is attached thereto by a bolt 20, said bolt passing through a slot 21 to allow the box to be adjusted on the shelf F toward and away from the rolls B^1 , B^2 . Depending lugs on 40 the box 19 are provided with set screws 22, 22 by which the position of the box on the shelf F is determined. The receiving guide box 19 consists of a bottom 23 and a pair of vertical sides 24, 24, which are open at the 45 top, and between which are held a pair of adjustable cheek-plates 25, 25. The cheek-plates 25 are attached near one end to the sides of the box 19 by bolts 26, and their free ends are crowded toward each other by 50 a pair of wedges 27 which may be driven down in slots 28 formed in the sides 24, until the free ends approach each other sufficiently to restrain the movement of the metal as it passes between them and guide it into the 55 pass of the rolls B^1 , B^2 . As each of the cheek-plates is independently adjustable their lateral position may be varied to bring the metal into alinement with the pass between the rolls. The bottom 23 of the receiving guide box is recessed to receive a removable bottom piece 29 which supports the greater portion of the cheek-plates 25. Supported upon the upper edges of the cheek-plates 25 is a cover 30 which is compressed 60 against the cheek-plates by means of a 65

wedge 31 acting against a transverse plate 32 having its ends held in slots 33 in the sides 24 of the guide box 19.

At or near the receiving end of the conveyer trough 18 an opening 34 is provided in the bottom of the trough, which is covered by a swinging plate 35, hinged upon a rod 36 held in the delivery guide box 1. Attached to the under side of the plate 35 is a bracket 37 pivotally connected by a link 38 with an 70 arm 39, carried on a rocking shaft 40, to which a lever 41 is attached, which serves as a handle by which the shaft 40 may be rocked for the purpose of lifting the plate 35 into the position shown by broken lines 42. 75 The conveyer trough 18 has one of its ends resting upon the bottom 23 of the receiving guide box 19, and having its sides at the opposite end resting upon the rod 36 held in the delivery guide box 1. The function of the swinging plate 35 is to raise the moving metal as it passes through the conveyer trough 18 to allow it to form a loop above the conveyer trough and thereby provide for an overfeed of metal between the consecutive 80 pairs of rolls, and to accomplish this purpose the swinging plate 35 is placed at the initial end of the conveyer trough and in close proximity to the delivery guide box 1 and the stripping plates 10 and 15, in order that the 85 metal may be deflected from a direct path through the conveyer trough at the initial end of its support between the successive pairs of rolls, in order that a maximum length of the rolled metal may be taken up by the 90 loop with a minimum elevation of the deflecting plate 35; the entire space between the two guide boxes being thereby practically available for the formation of the loop as indicated by the broken line 43 which shows 95 the position of the rolled metal between the two pairs of rolls. In order to prevent the loop from falling sidewise, I erect upon the trough 18 the guide stakes 44, which are removably held in sockets 45 attached to the 100 sides of the trough 18.

What I claim as my invention and desire to secure by Letters Patent is:—

1. In a rolling mill, the combination with a roll housing and a pair of rolls journaled therein, of a guide box on the delivery side of said rolls, comprising a pair of vertical sides, a lower stripping plate held in said guide box, a block frictionally held between the sides of said box and forming an abutting wall for an upper stripping plate, and an upper stripping plate. 115

2. In a rolling mill, the combination with a pair of rolls, and a guide box supported on the delivery side of said rolls and having a 120 pair of vertical sides, of a block frictionally held between said sides, and having a projection on the side next the rolls, and a stripping plate having one end held in contact with said rolls, and its opposite end in contact 125

130

with said block beneath said projection, whereby the end of said stripping plate is held from upward movement and, in one direction, from longitudinal movement.

3. The combination with a pair of rolls of a rolling mill, and a guide box supported on the delivery side of said rolls, and comprising a pair of vertical sides, of a block having one end bearing against one of the sides of said box, and a set screw held in the opposite side of said box and bearing against the opposite end of said block, whereby said block is frictionally held in position, and a stripping plate having one end in contact with said block.

4. The combination with a pair of rolls of a rolling mill, and a guide box supported on the delivery side of said rolls, and comprising a pair of vertical sides, of a block frictionally held between said sides, a stripping plate having one end held by said block, and yielding means of suspension by which the free end of said stripping plate is held against the periphery of one of the rolls of said pair.

5. The combination with a pair of rolls of a rolling mill, of a guide box supported in proximity to said rolls, said guide box having a bottom provided with a shoulder and an inclined surface between said shoulder and the rolls, and a stripping plate having one end bearing against said shoulder and extending over said inclined surface and out of contact therewith, with its opposite end supported by the periphery of the lower roll in said pair.

6. The combination with a pair of rolls of a rolling mill, of a guide box supported in proximity to said rolls and comprising a bottom and a pair of vertical sides, a block frictionally held between the sides of said guide box, with one of its ends in contact with one of said sides, means for applying pressure to the opposite end of said block, and a stripping plate bearing against said block.

7. The combination with a pair of rolls of a rolling mill, of a guide box support held in a fixed position, and having a projecting shoulder on its upper surface, a guide box resting on said support and having a projecting shoulder on its under surface, and a wedge inserted between said shoulders, whereby said guide box is adjusted in position on said support.

8. The combination with two pairs of rolls in a rolling mill, arranged for the consecutive reduction of metal, of a guide box supported on the delivery side of the first pair of rolls, a conveyer trough leading from said guide box to the second pair of rolls, a plate at the entrance of said trough hinged transversely to the line of movement of the metal through said trough, and means for rocking said hinged plate.

9. In a rolling mill comprising a series of rolls, the combination with two consecutive pairs of rolls, of a conveyer trough interposed

between said pairs of rolls, a hinged plate at the bottom of said trough and at its initial end and extending from its pivot in the direction of the movement of metal through said trough, and means for raising said plate.

10. In a rolling mill, the combination with a pair of rolls, of a conveyer trough leading from the delivery side of said pair of rolls, said trough having an opening in its bottom, a hinged plate extending over said opening, a rock shaft journaled below said plate, an arm carried by said rock shaft, a link connecting said arm and said hinged plate, and a lever handle for rocking said rock shaft.

11. The combination with a pair of rolls, of a rolling mill, of a guide box supported on the receiving side of said pair of rolls, and comprising a bottom, a removable piece held on said bottom, a pair of adjustable cheek-plates attached at one end to said guide box, wedges for adjusting the free ends of said cheek-plates, a cover resting on said cheek-plates, and means for tightening said cover against said cheek-plates.

12. In a continuous rolling mill, the combination with a pair of rolls arranged to deliver the rolled metal to a second pair of rolls, a second pair of rolls, a support for the rolled metal between said delivery rolls and said second pair of rolls, means for deflecting the rolled metal from its direct line of movement on said support, said deflecting means being placed at the initial end of said support and normally held from movement during the passage of the metal.

13. In a continuous rolling mill, the combination with two consecutive pairs of rolls and a support for the rolled metal as it passes from one pair of rolls to the next successive pair of rolls, of a plate hinged at one end in the plane of said support, and at the initial end thereof, with its free end extending in the direction of the line of movement of the rolled metal, and means for swinging said plate.

14. In a rolling mill, the combination with a conveyer bar supporting the rolled metal between consecutive pair of rolls, of means for raising the rolled metal from said support to form a loop, and vertical stakes projecting above said support to prevent the swinging movement of the loop.

15. The combination with a conveyer trough for conducting the rolled metal from one pair of rolls of a rolling mill to the next consecutive pair of rolls, of means for raising the rolled metal from said trough to form a loop, stake sockets attached to the sides of said trough and vertical stakes removably held in said sockets.

125

Dated this second day of October 1905.
